UNITED STATES PATENT OFFICE.

LILLIAN C. ADAMS, OF SUMMERTON, GEORGIA.

COMBINATION STOVE LINING AND GRATE ASSEMBLY.

1,314,845.

Specification of Letters Patent. Patented Sept. 2, 1919.

Application filed August 1, 1918. Serial No. 247,874.

To all whom it may concern:

Be it known that I, LILLIAN C. ADAMS, a citizen of the United States, residing in the city of Summerville, State of Georgia, have invented new and useful Improvements in Combination Stove Linings and Grate Assemblies, of which the following is a specification, reference being had to the accompanying drawings.

10 This invention relates to combination grates for stoves, and the primary object thereof is to provide a combination grate which may be adjusted to any ordinary stove, and adapted therein for the burning of either coal or wood as desired.

15 A further object is to provide a grate of this character which may be quickly and easily secured within the stove without using bolts or screws for the purpose.

20 With these and other objects in view attention is called to the accompanying drawings, wherein—

Figure 1, is a perspective view of a stove equipped with my invention, a section being 25 out to show the arrangement of the linings and parts within the stove;

Fig. 2, is a detail showing the method of assembling and locking together the side and back linings and the grate bar;

30 Fig. 3, is a detail showing the method of affixing the supports;

Fig. 4, is a detail showing a formation and adjustment of the grates; and,

35 Fig. 5, is a perspective view of one of the supporting standards.

In the accompanying drawings "S" designates a stove having the front "F," the stove being provided with the usual ash pan "A." Located within the stove is a rectangular channeled supporting frame, comprising the flat outer circumscribing flange 5', and the inner skirting flange 3', the channel portion 5 having the openings 2' shown in Fig. 2.

40 Four standards, designated 10, 11, 12 and 13, respectively, support this frame, the forward end of the latter resting against the front "F."

Retained on this frame member is the rear lining 6, provided with stub side wings w, w, from which extend the vertically disposed lugs 30 and 31 shown in Fig. 2, said lugs having the inwardly directed pins 32, 33. Two side linings 7 and 8 are held on the

outer flange 5', these linings each having 55 suitable rear end openings 36 arranged for coaction with the pins 32, 33, while the downwardly directed lugs "b" are arranged to seat in the openings 2'. Each side lining has a front end hook 7' arranged 60 to lock over said outer flange 5' to hold the side linings in place.

Held within the bearings 14, 15, 18 and 19 are the pivots 21 and operating stems 40, the front stems 40 being provided with the 65 meshing pinions 38 and 39 as shown in Fig. 4.

As shown, an upper feed door opening and lower ash door openings are provided.

The member 5' is also provided with key 70 holes 24 and 25 at its rear and front ends to receive and hold the locking studs 26, 27, 28 and 29, projecting from the upper surface of the supports 10, 11, 12 and 13.

The pinions 38 and 39 may be rigidly 75 mounted upon the pivots 18 and 19, in mesh with one another so that when one of said grates is rocked the other will move in unison. A projecting crank end 40 extending from the forward end of one of the 80 grates as at 22, provides for the attachment of the crank 41 for the purpose of rocking the grates and releasing the ashes.

While I have described herein a certain form and method of construction it will be 85 understood that the same is merely the preferred embodiment of the invention and I therefore reserve the right to make any desired changes without departing from the spirit and scope of the appended claim. 90

Having thus fully described my invention what I claim is—

The combination with a stove including a front having a feed opening and an ash door opening, of a rectangular channeled 95 supporting frame including a flat circumscribing outer flange and an inner upstanding skirting flange, standards supporting said frame at a point to divide said stove into an upper firepot and a lower ash chamber, a back lining having stub side wings arranged to rest on said outer flange, vertically disposed lugs extending from the ends of said wings having inwardly directed pins, the side members of said frame having 100 suitable openings, the forward end of said frame resting against the inner face of said front, said skirting flange and channel por-

tion having alined front and rear bearings respectively, two side linings each having rear end openings to receive said pins and downwardly directed lugs for engagement with said openings, each side having a front end hook to lock over said outer flange, and two grate bars each ending in a rear stem

for coaction with said rear bearings and forwardly directly operating stems extending through openings in said stove front.

LILLIAN C. ADAMS.
